UNITED STATES PATENT OFFICE.

FRANCIS B. McDANIELS, OF OWATONNA, MINNESOTA.

STRAW-RACK FOR THRESHING-MACHINES.

SPECIFICATION forming part of Letters Patent No. 617,116, dated January 3, 1899.

Application filed January 25, 1897. Serial No. 620,714. (No model.)

To all whom it may concern:

Be it known that I, FRANCIS B. McDANIELS, of Owatonna, Steele county, Minnesota, have invented certain new and useful Improvements in Straw-Racks for Threshing-Machines, of which the following is a specification.

This invention relates to improvements in straw-racks for threshing-machines; and the object I have in view is to provide a straw-rack that is applicable to any threshing-machine and that will secure a thorough and complete separation of the grain from the straw while it is passing over the rack.

15 The invention consists generally in a straw-rack provided with double-acting reciprocating rack-bars alternately arranged, whereby the straw is carried forward by the reciprocating movement of the alternating bars.

20 The invention further consists in oscillating or reciprocating and oscillating blades or lifting-fingers arranged either separately or in conjunction with the reciprocating bars of the rack.

25 The invention consists, further, in adjustable means for operating the rack-bars and lifting fingers or blades either together or independently of each other.

The invention consists, further, in a peculiar construction of the bars of the rack.

The invention consists, further, in double-acting reciprocating grain-pans arranged in connection with the double-acting racks or blades.

35 The invention consists, further, in the various constructions and combinations herein-after described, and particularly pointed out in the claims.

The invention will be more readily understood by reference to the accompanying drawings, in which—

Figure 1 is a longitudinal section of a portion of a threshing-machine, showing my improved straw-rack arranged therein. Fig. 2 is a detail plan view of a portion of one of the

40 rack-bars. Fig. 3 is a section on line 2 2 of Fig. 2. Fig. 4 is a partial side elevation of the rack-bar shown in Fig. 2. Fig. 5 is a transverse section on line 4 4 of Fig. 4. Fig. 50 6 is a plan view of a portion of one of the rack-bars, showing a modified form of a portion of the surface. Fig. 7 is a section on

line 6 6 of Fig. 6. Fig. 8 is a partial side elevation of the rack-bar shown in Fig. 6. Fig. 9 is a section on line 8 8 of Fig. 8. Fig. 10 is 55 a side elevation showing a modified construction and arrangement of the blades or lifting-fingers. Fig. 11 is a plan view of the blades shown in Fig. 7. Fig. 12 shows another modification of the lifting blades or fingers and the 60 means for supporting and operating the same. Fig. 13 is a plan view of the parts shown in Fig. 12. Fig. 14 is a side elevation and partial section showing another modification of the lifting fingers or blades and the means for 65 supporting and operating the same. Fig. 15 is a partial transverse section on line 1 1 of Fig. 1. Fig. 16 is a plan view of a portion of the rack shown in Fig. 15. Fig. 17 is a detail of the adjustable pitmen. Figs. 18 and 19 are 70 details showing the manner in which the lifting-fingers shown in Figs. 12 and 13 may be constructed and the means by which they may be secured to the shaft.

In the drawings, 1 represents the inclosing 75 frame or casing of a threshing-machine, which may be of any ordinary or preferred construction. It is provided with the usual feeding-table 2 and threshing-cylinder 3 and may also be provided with the usual depend- 80 ing curtains 4. Arranged in the casing below the straw-rack are suitable grain-pans. I have here shown and prefer to employ suitable pans 5, arranged to overlap each other and suspended on pivoted hangers 6. These 85 pans are given a reciprocating movement by means of the pitman 7 and crank-shaft 8, said crank-shaft being preferably provided with a suitable driving-pulley 9. The crank-shaft is supported upon the frame of the 90 machine by bearings of any preferred construction. The cranks 8 are preferably oppositely arranged, so as to cause said pitmen to move in opposite directions, thereby giving to said pans a double action or causing them 95 to reciprocate at the same time in opposite directions.

Arranged above the grain-pans and in position to receive the straw after it has passed the cylinder is the straw-rack forming the 100 principal feature of this invention. In the following specification and claims I have designated the part of the straw-rack that is toward the cylinder and upon which the

grain is received from the cylinder as the "head." This rack consists, essentially, of two series of rack-bars alternately arranged and provided with means for reciprocating said bars, the arrangement being such that the bars of one series have an opposite reciprocation from the bars of the other series—that is to say, one series of bars move forward as the others move back, and vice versa. Each rack-bar 11 is provided upon its upper surface with a series of notches, each notch having at its rear end an abrupt shoulder 12, and the alternate notches are preferably formed with a rounding or curved upper surface, as shown in Figs. 2, 4, and 5, or with laterally sloping or inclined surfaces, as shown in Figs. 6, 8, and 9. Each series of bars 11 is supported upon suitable cross-bars, preferably by being rigidly secured thereto. As here shown, one series of rack-bars 11 is supported upon the cross-bars 13 13 13, while the other series are supported upon the cross-bars 14 14 14. It will be understood, however, that any suitable number of cross-bars may be employed for each series of rack-bars. The said cross-bars 13 are pivotally supported, as shown in Figs. 15 and 16, to the upper ends of the hangers 6 of one of the grain-pans 5 and to a short hanger 6', pivotally supported upon the frame of the machine. The other series of cross-bars 14 are pivotally supported, as shown in Fig. 16, upon the upper ends of the hangers 6 of the other grain-pan and upon a short hanger 6", also pivotally supported 35 upon the wall or frame of the machine. It will be seen that as the grain-pans are reciprocated the rack-bars 11 will be given an opposite reciprocating movement, and that thereby the straw falling upon said rack-bars 40 will be rapidly moved along over the surface of the rack, and that as one series of bars move forward while the other moves backward the straw will be picked up by one set of bars at the points where it is left by the other set of rack-bars. As the bars move forward the abrupt shoulders 12 thereon engage the straw and cause it to move forward or toward the tail end of the machine with the bars, and as said rack-bars move backward the straw does not move with them, but is left at the points to which it is carried in the forward movement of the bars, at which points it is picked up by the other series of bars and given a further forward 50 movement.

As shown in the detail views, Figs. 2 to 8, and also in Figs. 15 and 16, I prefer to make each rack-bar with a series of notches having flat upper surfaces alternating with notches having laterally inclined or rounded upper surfaces. The purpose of this construction is to enable me to secure two notches in a given depth of the bar, each having a gradual or slight incline to its upper surface, so as to cause but slight friction or resistance between this inclined surface and the straw when the rack is receding or moving back-

ward and leaving the straw. Moreover, any grain lodged upon the flat surface of one notch will as it passes over onto the next succeeding notch slide off laterally and drop upon the grain-pans below.

I prefer to provide the rack with a series of lifting fingers or blades, preferably arranged also in two series and between the bars of the rack. These blades may be formed of sheet metal, wire, or other suitable material. As shown in Figs. 1, 10, 11, 15, and 16, said blades are formed of sheet metal and are provided upon their upper surfaces with a series of notches substantially in the shape of saw-teeth. As shown in Figs. 1, 15, and 16, these blades 15 are secured to suitable cross-bars 16, and said cross-bars are rigidly secured to the hangers that support the rack. Any other suitable means of supporting said blades or lifting-fingers may, however, be used. With the arrangement shown in Figs. 1, 15, and 16 as one series of rack-bars retreat or move backward the corresponding series of lifting fingers or blades move in the same direction and at the same time are depressed or tipped downward, so that when said bars reach the limit of their backward movement the upper surfaces of said blades or lifting-fingers are substantially on a level with the upper surfaces of said rack-bars. As the rack-bars are moved in the opposite direction the lifting fingers or blades are elevated and projected above the upper surfaces of the rack-bars. This movement of the blades is clearly illustrated by the full and dotted lines indicating the different positions of said blades in Fig. 1 of the drawings. These lifting fingers or blades aid in the movement of the straw over the surface of the rack and at the same time as said fingers or blades are quickly projected upward between the bars they lift and shake up the straw, thereby aiding in shaking out the grain from the straw. They also tend to throw forward the straw, and as said blades are alternately arranged those of one series move in opposite directions from those of the next series. The straw or considerable portions of it will be tossed from one series of blades to the next series, and so on throughout the machine. While I prefer to move the blades alternately in opposite directions and to support said blades upon the hangers by which the racks are operated, it will be understood that I do not confine myself to such means for supporting or operating said blades or lifting-fingers. While in the construction shown in Figs. 1, 15, and 16 said blades or lifting-fingers have both a reciprocating and an oscillating movement, being tipped or tilted by the hangers upon which they are supported and being carried bodily forward and backward by the movement of said hangers, such movement is not essential to the operation of the device, and in Figs. 10 and 11 of the drawings I have shown the blades or lifting-fingers 15 mounted upon

shafts 18, by which said blades or lifting-fingers may be given an oscillating movement only. The blades when thus arranged may be located substantially as shown in Figs. 1, 5 15, and 16 in relation to the reciprocating rack-bars 11, or the rack-bars may in this instance and also with the construction and arrangement of blades or lifting-fingers shown in Figs. 1, 15, and 16 be omitted.

10 In Figs. 10 and 11 I have shown the blades arranged to alone form the straw-rack, the reciprocating bars being entirely omitted. When the bars are not employed, it will be understood that a greater number of blades 15 will be used. As shown in Figs. 10 and 11, the blades are arranged so as to overlap each other in series, and the shafts 18 being rocked by any suitable means the blades 15 will be tilted or oscillated, and thereby the straw will 20 be moved over the rack and the grain will be shaken therefrom and will drop down between the blades onto the grain-pans below.

In Figs. 12, 13, and 14 I have shown the blades or lifting-fingers formed of wire, with 25 their upper surfaces straight, as shown in Fig. 12, or made of saw-tooth form, as shown in Fig. 14. In Figs. 12, 13, and 14 I have also shown the shafts 18 mounted in suitable bearings upon reciprocating bars 20, there being 30 preferably one of said bars at each side of the machine. These bars are suitably supported, as by means of the pivoted hangers 21, and they are connected to the reciprocating grain-pans or to the pitmen 7 or to other 35 suitable means by which they may be given a reciprocating movement. To the end of each shaft 18 is connected a crank-arm 22, provided with an opening or slot and connected by a pin or other suitable means to the 40 frame or easing of the machine. The crank-arms of one series of said shafts 18 extend downward and those of the other series extend upward. By this means as the bars 20 are reciprocated the blades or lifting-fingers 45 15 will be oscillated, the alternate series of blades moving in opposite directions, and by this means the blades or lifting-fingers will operate to rapidly move the straw over the rack and at the same time to shake the grain 50 therefrom.

In Fig. 17 I have shown the pitman 7 made in two sections overlapping each other, each section being provided with a series of holes 25, with bolts 26 for bolting said sections together. By this means the pitman can be 55 lengthened or shortened, and thereby the movement of the parts operated therefrom may be regulated or adjusted. In this way I can regulate the movement of the rack-bars 60 and blades as occasion may require.

In Figs. 18 and 19 I have shown the lifting-finger 15 formed by overlapping the ends of the wire of which it is constructed in a suitable clamp 28, that is secured to the shaft 18 65 by means of a set-screw 29, the two parts of the clamp being drawn together for the purpose of clamping the wire by means of a bolt 30.

In Fig. 14 I have shown the lifting-fingers 15 secured to a suitable board 31, as by means of the eyebolts or staples 32, and the board 31 70 may be supported upon the shaft 18 by a suitable bracket 33.

I do not limit myself to the details of the construction of the rack-bars or lifting blades or fingers or to the details of the mechanism 75 for supporting and operating said parts, as it is obvious that the same may be varied in many particulars without departing from my invention.

Having thus described my invention, I 80 claim as new and desire to secure by Letters Patent—

1. The combination, with the two series of oppositely-reciprocating rack-bars and means for moving said bars, of the tilting and reciprocating blades or fingers, the end of each blade or finger that is toward the head of the rack being arranged to rise higher than the opposite end as the rack-bar is moved, and means for positively tilting and reciprocating 85 said blades or fingers, for the purpose set forth.

2. The combination, in a straw-rack for threshing-machines, with the two series of rack-bars alternately arranged, and means 95 for moving said bars in opposite directions, of the two series of tilting and reciprocating blades or lifting-fingers the end of each blade or finger that is toward the head of the rack being arranged to rise higher than the opposite end as said blade or finger is tilted, and means for positively tilting and reciprocating 100 said blades or fingers, for the purpose set forth.

3. The combination, in a straw-rack for threshing-machines, of a series of pivotally-supported blades or lifting-fingers, the end of each blade or lifting-finger that is toward the head of the rack being arranged to rise higher than its opposite end, and means for positively 105 tilting and reciprocating said blades or fingers, for the purpose set forth.

4. The combination, in a straw-rack for threshing-machines, of a series of reciprocating pivotally-supported blades or lifting-fingers, the end of each blade or finger that is toward the head of the rack being arranged to rise higher than its opposite end, means 115 for reciprocating said blades or fingers, and means for positively tilting said blades or fingers, for the purpose set forth.

5. The combination, in a straw-rack for threshing-machines, of a series of alternately-arranged and overlapping blades or fingers, pivoted arms or hangers upon which said 125 blades are supported in a fixed position, said blades projecting from said hangers toward the head of said straw-rack, means for reciprocating said blades or fingers, and means for positively tilting said blades or fingers, for 130 the purpose set forth.

6. The combination, in a straw-rack for threshing-machines, of a series of alternately-arranged and overlapping blades or fingers,

pivoted arms or hangers upon which said blades are supported in a fixed position with the main portions of said blades projecting from said hangers or arms toward the head 5 of the straw-rack, and means for oscillating said hangers, whereby said blades or fingers are given a positive reciprocating and tilting movement and the ends of said blades that are toward the head of the straw-rack being 10 arranged to rise higher than the opposite ends.

7. The combination, in a straw-rack for threshing-machines, of a series of blades or lifting-fingers, pivoted arms or hangers upon 15 which said blades or fingers are supported, said blades or fingers projecting from said hangers toward the head of the straw-rack, and means for oscillating said hangers, whereby said blades or fingers are given a reciprocating and positive tilting movement and the ends of said blades that are toward the head of the straw-rack are caused to rise higher than the opposite ends. 20

8. The combination, in a straw-rack for threshing-machines, with reciprocating rack-bars, of a series of blades or fingers, pivoted arms or hangers upon which said blades or fingers are supported, said blades projecting from said arms or hangers toward the head 25 of the straw-rack, and means for oscillating said hangers, whereby said blades or fingers are given a reciprocating and positive tilting movement. 30

9. The combination, in a straw-rack for threshing-machines, with reciprocating racks, 35

of a series of blades or lifting-fingers, pivoted arms or hangers upon which said blades or fingers are supported in a fixed position and projecting from said arms or hangers toward the head of the straw-rack, and means for moving said hangers, whereby said blades or fingers are given a reciprocating and tilting movement and the ends of said blades or fingers that are nearest the head of the straw-rack are caused to rise higher than the opposite ends, for the purpose set forth. 45

10. The combination, in a straw-rack for threshing-machines, with the two series of rack-bars 11 alternately arranged, cross-bars supporting said rack-bars, hangers supporting said cross-bars, lifting blades or fingers 15 supported in a fixed position upon said hangers, and means for oscillating said hangers, for the purpose set forth. 50

11. The combination, in a straw-rack for threshing-machines, with the two series of rack-bars 11 alternately arranged, cross-bars supporting said rack-bars, hangers supporting said cross-bars, the lifting blades or fingers arranged between said rack-bars and carried 60 by said hangers, the grain-pans also supported upon said hangers and means for operatively reciprocating said grain-pans, for the purpose set forth. 65

In testimony whereof I have hereunto set my hand this 12th day of January, A. D. 1897.

FRANCIS B. McDANIELS.

In presence of—

A. C. PAUL,
M. E. GOOLEY.
